OF CHICAGO, ILLINOIS.

ELECTRICAL CONNECTOR.

1,255,943.

Specification of Letters Patent. Patented Feb. 12, 1918.

Application filed August 14, 1916. Serial No. 114,880.

To all whom it may concern:

Be it known that I, PARKE T. SNYDER, a citizen of the United States, residing at Chicago, in the county of Cook and State 5 of Illinois, have invented certain new and useful Improvements in Electrical Connectors, of which the following is a specification.

My invention relates to improvements in 10 electrical connectors and more particularly to a socket for receiving either a single or double contact Edi-Swan plug or lamp base.

One of the objects of my invention is to 15 provide an electrical socket arranged for use in either a single or double wire system and adapted to cooperate with either a single or double contact base irrespective of the character of system in which it is connected.

Another object of the invention is to 20 provide such a socket particularly adapted for automobile lighting circuits, a single stock type of socket serving for use in whichever system is employed by the car manufacturer and permitting the use of either single or 25 double contact on either wiring system.

A further object of the invention is the 30 provision of a sturdy, reliable, and efficient socket which may be manufactured at a low cost.

Still other and further objects of my 35 invention will become apparent to those skilled in the art from a consideration of the following specification and drawing; wherein;

Figure 1 is a diametrical sectional view 40 through a connector embodying my invention.

Fig. 2 is an end elevation of the same.

Fig. 3 is a transverse sectional view on the line 3—3 of Fig. 1.

Fig. 4 is a side elevation of the body part 45 of the connector removed from its shell.

Fig. 5 is a section on the line 5—5 of Fig. 3.

Fig. 6 is a diametrical sectional view 50 through a modified form of socket embodying my invention.

Fig. 7 is a transverse sectional view on the line 7—7 of Fig. 6, and;

Fig. 8 is a transverse sectional view on 55 the line 8—8 of Fig. 6.

Referring to the drawings, I have illustrated in Figs. 1 to 5 inclusive, a connector for joining two plugs, or a plug and lamp base, whereas in Figs. 6 to 8 I have illustrated a modification in the form of a socket

with means for attachment of wire terminals, the socket being adapted to receive either a connector plug or lamp base.

In both types of apparatus the connector is adapted for use in either a single or a 60 two wire system and for cooperation, irrespective of the system in which it is connected with either a single or double contact plug or lamp base.

In general the device comprises a tubular 65 metal shell 10 within which is positioned a contact-carrying cylinder or body part 11 of suitable insulating material, such as fiber, bakelite or the like. Referring particularly to the modification shown in Figs. 1 to 5 70 inclusive, I have shown a connector in which the tubular shell 10 is open at opposite ends and slotted as at 12 to receive the radially extending locking pins of an Edi-Swan plug. The body part or insulating block 11 75 is of a diameter sufficient to make a tight fit within the shell 10, so that after the contact parts are assembled in the block it is pressed into position in the shell 10, there being sufficient frictional resistance to hold it in place, 80

Two cylindrical openings 13 and 14 extend through the insulating block on lines parallel with its axis and positioned, as illustrated in Fig. 3 in the same diametrical plane at approximately equal distances from 85 the axis of the cylinder. Within these two openings are positioned a pair of telescoping, resiliently extended, tubular contact members A and B.

The contact member A comprises a tubular member 15, the upper end 16 of which is closed, its lower end telescoping over the open end of a similar tubular member 15', the lower end 17 of which is closed and serves as a contact for the lower socket. A 90 coiled spring 18 fits within the two telescoping tubes and serves to resiliently hold the contacts in their outermost position. A rectangular slot 19 extends from each end of the cylindrical plug 11 between its periphery 100 and the hole 12 inwardly at an angle to intersect the tubular opening 13 about one quarter of its length from the ends. Within these slots are positioned thin metallic leaf springs 20, the outer free ends of which 105 contact with the inner wall of the metal shell 10 and the inner ends of which are fastened, as by means of solder, to the tubular members 15 and 15'. Movement of either of the tubular members 15 or 15' inwardly against 110

the action of the coiled spring 18 causes the leaf spring to which it is connected to be drawn into the slot in the insulating block and out of contact with the metal shell 10.

- 5 In assembling the contact member A the tubular member 15 is first inserted from the upper end into the opening 18 in the block and pressed inwardly until its leaf spring 20 snaps into the lower end of slot 19 after which it is moved in the reverse direction until it assumes the position shown in Fig. 1. The coil spring 18 is then inserted from the opposite end of the opening 18 and the tubular contact 15' pressed inwardly until 15 its leaf spring 20 slips into the inner end of its corresponding slot 19, whereupon the coiled spring 18 will force it outwardly into the position shown in Fig. 1. With such an arrangement it is obvious that either end 16 or 17 may be pressed inwardly against spring 18, such inward pressure drawing the corresponding leaf spring 20 out from engagement with the surrounding metal shell 10.
- 20 The other contact member B comprises two telescoping metal tubes 21, 22 positioned within the opening 14, and having their outer ends 23, 24, flattened over at one side, so as to overlie the central axial portion of the insulating block, as illustrated in Fig. 2. A coiled spring 25 is positioned within the telescoping tubular members to resiliently hold them in their outermost position. The inner end portions of the tubular members 21 and 22 are slotted as at 26 and 27 at the side diametrically opposite the bent over end portions 23 and 24, to receive a screw-threaded pin 28 which extends radially inwardly through an opening 29 in the block to serve 35 as a stop to prevent outward movement of the two tubular members beyond the position shown in Fig. 1.

With such an apparatus either end of the socket is adapted to receive either a single 40 or double contact plug or lamp base and make proper electrical connection. For example, if a single contact lamp is inserted in the upper end of the socket, its centrally positioned contact will engage with the over-turned end 23 of contact member B and depress the same without affecting contact A which is in electrical connection with the side of the shell 10 and therefore in contact with the return circuit of the lamp through 45 the metal wall of its base. If a double contact plug is inserted in the lower end of the connector the two contacts of the plug will engage with the two contacts 17 and 24 respectively, pressing both of them inwardly 50 freeing the lower leaf spring 20 from contact with the wall 10. Thus a two wire system is made to feed a single contact lamp, and similarly a single wire system may be used to feed a double contact lamp.

55 In the standard single point Edi-Swan

lamp base or plug the central contact is raised above the end of the base upon a frusto-conical insulator from the bottom of which radiates a metallic ring merging at its periphery into the metallic side wall of 70 the base. The insulator in the standard base extends to points so close to the periphery of the ring that when such a base is inserted in the socket illustrated it will be evident that the insulator will engage near its bottom portion with the socket contact 16 or 16'. If, however, the lamp base is built so that the insulator for the center contact is small enough not to overlie the socket contacts 16 or 16' the side shell contacting 75 springs 20 or 20' will not be necessary. In my copending application for electrical connectors filed December 14th, 1916, and Serial No. 136,933 which, in so far as it relates to certain features of the subject matter disclosed in Figs. 6, 7 and 8 of the drawings of this application is a continuation of the present application, I have disclosed and claimed an improved socket with the contacts so arranged that when used with the 80 standard bases the connecting spring 20 or 20' is not necessary.

In Figs. 6, 7, and 8 I have shown a modification of the invention in which a lamp socket is provided with wire clamping terminals suitable for connection in either a single or double wire system. In the metal shell 10' is inserted a cylindrical body part 11' of insulating material, within which are positioned the lamp base or plug contacting 95 terminals C and D. The lower end of the body part 11' extends slightly beyond the lower end of the tubular shell 10', whereas its upper end is positioned within the shell 10' to provide a socket with the usual slot 100 openings 12' for receiving an Edi-Swan lamp base or plug.

The contact member C comprises a tubular insert 15^a having a solid head 17' at its lower end, its upper end being open to receiving telescoping tubular contact member 15^b the upper end 16' of which is closed to serve as a contact. The lower open end of the tubular member 15^b is flanged outwardly and after it is inserted in position with its 110 coiled spring 18' the upper end 16^b of tube 15^a is flanged inwardly and the wall of tube 15^a is dented in as at 40 to prevent its displacement. A leaf spring 20' is soldered to the tubular member 15^b near its upper end and 115 projects outwardly at an angle so that when in its upper position, as illustrated in Fig. 6 it will make secure contact with the shell 10'. In order to properly position the spring 20' and prevent its rotation about the axis 120 of the contact the upper end of the shell 15^a is cut away as at 19' at the side adjacent the periphery of the plug 11' to receive the spring 20'. An axial opening 30 is drilled 125 in the head 17' at the lower end of the tube 130.

15^a and coincides with a similar opening 31 provided in the insulating block 11' to receive a wire 32 which may be clamped in position by the obliquely extending screw 33 which is so arranged that when a wire is in the opening 30 in the head the screw clamps the same in place, but if no wire projects into the opening the screw is of sufficient length to project entirely through 10 the head 17' and into engagement with the shell 10' at the opposite side of the contact C, thus grounding the terminal C to the shell.

The other contact D is formed similarly 15 of a tubular member 22' having a head 24' at its lower end, its upper end being open to receive the telescoping tubular member 21' the upper end of which is flattened over as at 23' to overlie the inner end of the plug 20 11' as in the heretofore described connector. The coiled spring 25' is positioned within the tubular telescoping members 21' and 22', a slot 26' being provided in the tubular member 21' near its inner end for engagement 25 by the threaded pin 28' which extends into the body of the connector to serve as a limiting stop as in the heretofore described embodiment. The lower end or head 24' of the tube 22' is axially bored as at 24 to 30 receive the end of a connecting wire 35 which is securely held in contact with the tube by means of an obliquely extending screw 36 which takes through from the periphery of the plug 11' into the head 24'.

35 By this arrangement either a single or double wire system may be used for connection with a single or double contact lamp. For example, if we consider that the two wire system is employed as illustrated in 40 Fig. 6 it is obvious that if a single point lamp is inserted in the open end of the plug its center contact will engage with the contact 23', whereas its peripheral metal surface will engage the shell 10' and return to wire 32 through the spring 20' and tube 15'. The insertion of a two contact lamp will cause the depression of both contacts C and D freeing the spring 20' from its ground through the shell and leading the current from both 45 wires 32 and 35 directly to the two contacts of the lamp. If a single wire system is to be employed the single wire is led into terminal D and the screw 33 for the other terminal is run through the head 17' to make 50 grounded contact with the shell. With such an arrangement if a single contact lamp is inserted in the socket its center will, of course, make connection with the terminal 23' and thence to wire 35, whereas its peripheral contact surface will engage the shell 10' and from thence to ground. If a two contact lamp is inserted in the socket both contacts C and D will be depressed contact D carrying current through to wire 35, and 55 the other lamp contact making engagement

with the end 16' of terminal C will run to ground through the screw 33.

Whereas I have illustrated and described but two embodiments of my invention it will be obvious that various changes and modifications may be made therein without departing from the spirit and scope of the appended claims.

What I claim is:—

1. An electrical connector for coöperation 75 with either a single or double contact plug and comprising a metallic shell, an insulating body therein, a pair of resiliently extended contacts carried thereby, one contact over-lying the axis of the shell and projecting to one side thereof, the other contact positioned at one side of the axis, and a conductor carried by one of the contacts for engagement with the shell only when the last mentioned contact is in extended position. 80

2. An electrical connector for coöperation with either a single or double contact plug and comprising a metallic shell, an insulating body therein, a pair of resiliently extended contacts carried by the body part, one 90 contact over-lying the axis of the body part and projecting to one side thereof, the other contact positioned at one side of the axis, a conductor carried by one of the contacts for engagement with the shell when the contact 95 is in extended position, and means to move the conductor out from engagement with the shell when its contact is depressed.

3. An electrical connector for coöperation with either a single or a double contact plug, 100 comprising a shell, an insulating body part therein, a pair of resiliently extended contacts carried by the body part, means for electrically connecting one of the contacts with the shell when the contact is in extended position, and means for breaking the electrical connection when the last mentioned contact is depressed.

4. An electrical connector for coöperation with either a single or a double contact plug, 110 comprising a shell, an insulating body part within the shell, a pair of resiliently extended contacts carried by the body part, a spring carried by one of the contacts for engagement with the shell, and means operative on the depression of the last mentioned contact for moving said spring from engagement with the shell. 115

5. A socket comprising a shell, an insulating body part therein, a pair of resiliently 120 extended contacts carried by the body part, a member carried by one of the contacts and adapted normally to make electrical connection with the shell, and means for breaking said electrical connection when the last mentioned contact is depressed.

6. A socket comprising a shell, an insulating body part therein, a pair of resiliently extended contacts carried by the body part, one contact overlying the axis of the shell 130

and projecting to one side thereof, and the other contact positioned at one side of the axis, a conductor carried by the last mentioned contact and normally adapted to contact with the shell, and means operative upon the depression of said last mentioned contact for moving the conductor out from contact with the shell.

7. A socket for coöperation with either a single or a double contact plug and comprising a peripheral contact, a contact for engagement with either the single contact of a single contact plug or one of the contacts of a double contact plug, a contact for engagement with the other contact of a double contact plug, means for electrically connecting the last mentioned contact with the first mentioned contact when a single contact plug is inserted in the socket, and means for breaking said electrical connection when a double contact plug is inserted in the socket.

8. A socket for coöperation with either a single contact or double contact plug and comprising a metallic shell, a body part of insulating material therein having two longitudinally extending openings therein on opposite sides of the axis, a resiliently extended tubular contact having an end portion overlying the axis of the body part in one of the openings, a resiliently extended tubular contact in the other opening, a leaf spring carried by the last said contact extending angularly therefrom for engagement with the shell, and an abutment on the body part for engagement with the spring when its contact is depressed to cam the spring away from the shell.

9. A socket for coöperation with either a single contact or double contact plug and comprising a metallic shell, a body part of insulating material therein having two longitudinally extending openings therein on opposite sides of the axis, a resiliently extended tubular contact having an end portion overlying the axis of the body part in one of the openings, a resiliently extended tubular contact in the other opening, said body part having an angularly disposed slot extending from one of the openings outwardly away from the axis and a conductor positioned in said slot with its outer end adapted to make contact with the shell when the adjacent contact is in extended position, its inner end being secured to the adjacent contact.

10. An electrical connector comprising a metallic shell, a body part of insulating material positioned therein intermediate its ends to provide a plug receiving socket at each end, said body part having two longitudinally extending openings through the body part one at each side of the axis, a pair

of telescoping metallic tubes in each opening, a spring within each pair of tubes adapted to resiliently extend the same, means for limiting the longitudinal movement of the tubes, the ends of each tube of one pair being turned at right angles and flattened to overlie the axis of the shell at each end of the body part, conductors carried by each of the tubes of the other pair and adapted to make contact with the shell when the tubes are in extended position, and means associated with each conductor to move the same out from engagement with the shell when its corresponding tube is depressed.

11. An electrical connector comprising a metallic shell, a body part of insulating material positioned therein intermediate its ends to provide a plug receiving socket at each end, said body part having two longitudinally extending openings through the body part, one at each side of the axis, a pair of telescoping metallic tubes in each opening, springs adapted to resiliently extend the same, the ends of each tube of one pair being turned at right angles to overlie the axis of the shell at each end of the body part, an angularly disposed slot extending from near each end of the opening in which the other tubes are located outwardly from the axis and a leaf spring in each said slot adapted to make contact at its outer end with the shell when its corresponding tube is in extended position the inner end of each spring being secured to its corresponding tube.

12. An electrical connector for coöperation with either a single or double contact plug and comprising a metallic shell, an insulating body therein, and a pair of independently resiliently extended contacts carried thereby, one contact overlying the axis of the shell and projecting to one side thereof, the other contact positioned at one side of the axis.

13. An electrical connector for coöperation with either a single or double contact plug and comprising a metallic shell, an insulating body therein, a pair of independently resiliently extended contacts carried thereby, one contact overlying the axis of the shell and projecting to one side thereof, the other contact positioned at one side of the axis, and a conductor carried by one of the contacts and adapted to be moved into engagement with the shell.

In testimony whereof I hereunto set my hand in the presence of two subscribing witnesses.
